JIG

**Byron M. Bird, Columbus, Ohio, assignor, by
mesne assignments, to The Jeffrey Manufacturing Company, a corporation of Ohio**

Application August 28, 1943, Serial No. 500,417

2 Claims. (Cl. 209—457)

This invention relates to a jig, and an object of the invention is to provide mechanism to produce an excess of water against the washed coal overflow lip to increase the mobility of the bed along this area.

Other objects of the invention will appear hereinafter, the novel features and combinations being set forth in the appended claims.

In the accompanying drawing,

Fig. 1 is a sectional elevational view showing a jig incorporating the features of my invention; and

Fig. 2 is an enlarged plan view of a portion of the screen or perforated plate which supports the bed of material being treated, and taken on the line 2-2 of Fig. 1, looking in the direction of the arrows.

The principal structure of my jig may follow that disclosed in my Patent 2,132,376, entitled Method in jigging, dated October 11, 1938, and it is to be understood that unless a contrary fact is indicated, the jig of my invention follows the structure of this patent.

Briefly described, the jig includes a cleaning compartment 10 which is disclosed more completely in said patent and is of a Baum type and includes a U-shaped water column in which the water is pulsated by periodically admitting air under pressure to one side of the column, which air is stored in a tank 11 and controlled by valves 12. The bed of material, such as raw coal, which is to be treated, is developed on the screen or perforated plate 13 and the bed stratified, with the refuse in the bottom stratum and the clean coal on top. The raw coal is fed to the compartment by way of feed chute 14 and the cleaned coal is discharged over chute 15 after passing over a weir or lip 16 which controls the height of the liquid in the tank or compartment 10. Refuse is withdrawn by way of refuse chute 17 and refuse withdrawal mechanism 18, and the refuse bed is automatically maintained at a predetermined height under the control of float mechanism 19. Hutch material is delivered by a screw conveyor 20 to the boot of an elevating conveyor 21 by which it is elevated and discharged.

The structure so far described is found in my Patent No. 2,132,376 above mentioned.

The particular improvement which I have made is the provision of one or more rows of large holes 22 adjacent the lower end of the screen or perforated plate 13 so that along this area the screen has an increased open area as compared with the rest of the screen. As a

consequence of this structure, the open area adjacent the discharge chute 17 and which is also adjacent the overflow lip or weir 16, is increased by at least ten percent with reference to the open area through the rest of the screen or perforated plate 13. The result of this is to put an excess of water up against the washed coal overflow lip or weir 16. The purpose of this is to increase the mobility of the bed along this area since there is considerable friction due to the horizontal force exerted by the water flowing horizontally through the jig and over the weir or lip 16.

In the operation of the device the raw coal will be fed over the chute 14 and form a bed on the perforated plate or screen 13. The pulsating water will stratify the bed, with the refuse on the bottom and the clean coal on top, the clean coal being carried over the weir or lip 16 with the water and discharged by way of chute 15.

The float mechanism 19 will control the refuse discharge valve 18 to maintain the refuse bed within predetermined limits. The excess of water delivered adjacent the refuse discharge chute 17 and the plate leading up to lip or weir 16, will increase the mobility of the bed at this point or area and thus provide a more efficient cleaning of the coal.

30 To facilitate the use of increased open area in the screen plate adjacent the refuse discharge in increasing the mobility of the particles at that point, the percentage of open area in the balance of the screen plate should be reduced somewhat below that normally used. An example of a suitable plate is one with $\frac{1}{4}$ -inch perforation and 22 per cent of open area except at the refuse-discharge end where three rows of holes are used approximately $\frac{3}{4}$ inch in diameter and so spaced as to give approximately 30 per cent of open area.

40 Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In a jig, a material cleaning compartment, a perforated member forming the material supporting bottom thereof, a lip over which light material and water flows when leaving said compartment, said perforated member providing a substantially uniform percentage of open space

over most of its area, a refuse draw adjacent the discharge end of said perforated member and below said lip, means providing successive upward pulsations of water through said perforated member, and means including a narrow area immediately adjacent the discharge end of said screen provided with a single row of holes thereby providing for an excess of water flow adjacent said lip.

2. In a jig, a material cleaning compartment, a perforated member forming the material supporting bottom thereof, a lip over which light ma-

terial and water flows when leaving said compartment, said perforated member providing a substantially uniform percentage of open area of approximately 22 percent over its entire area except adjacent said lip where it is approximately 30 percent, and means providing successive upward pulsations of water through said perforated member, the aforesaid 30 percent open area being provided by a single row of holes in a narrow area immediately adjacent the discharge end of said screen.

BYRON M. BIRD.
